UNITED STATES PATENT OFFICE.

LOUIS W. CHISM, OF SPRINGFIELD, MASSACHUSETTS, ASSIGNOR, BY MESNE ASSIGNMENTS, TO WALSH-STANDARD STORE SERVICE, INCORPORATED, OF HARTFORD, CONNECTICUT, A CORPORATION OF CONNECTICUT.

CABLE CARRIER APPARATUS.

1,055,258.

Specification of Letters Patent. Patented Mar. 4, 1913.

Application filed February 28, 1912. Serial No. 680,509.

To all whom it may concern:

Be it known that I, LOUIS W. CHISM, a citizen of the United States, and residing at Springfield, county of Hampden, State of Massachusetts, have invented an Improvement in Cable Carrier Apparatus, of which the following description, in connection with the accompanying drawings, is a specification, like characters on the drawings representing like parts.

This invention relates to cable carrier apparatus, being more particularly concerned with so-called drop receiving and sending stations.

The invention will be best understood by reference to the following description, when taken in connection with the accompanying illustration of one specific embodiment thereof, while its scope will be more particularly pointed out in the appended claims.

In the drawings.—Figure 1 is a side elevation of one specific embodiment of the invention. Fig. 2 is a plan view of the same. Fig. 3 is an end elevation of the apparatus as viewed from the right hand side of Figs. 1 and 2. Fig. 4 is a detail perspective view showing the receiving and sending tracks of the station, and illustrating particularly the provisions for removing the carriers from the receiving track and introducing them on to the sending track. Fig. 5 is an elevation at an enlarged scale of a carrier upon the rails of the sending track just prior to its engagement with the grip closing cam. Fig. 6 is a detail elevation at an enlarged scale, viewed from the opposite side of the apparatus shown in Fig. 1, and illustrating the carrier with its gripping device in engagement with the cable just prior to its disengagement therefrom by the grip operating cam. Fig. 7 is a bottom plan view of the carrier as seen in Fig. 6, except that the carrier is moved along into position with the gripping device engaged by the grip releasing cam. Fig. 8 is an end view of the parts shown in Fig. 7. Fig. 9 is a detail view at an enlarged scale illustrating the action of the cable gripping lever and its operating spring. Fig. 10 is a detail view of the auxiliary sending track and its motor cable.

Referring to the drawings and to the embodiment of my invention which I have there disclosed for illustrative purposes, I

have there shown a cable carrier apparatus having a main outgoing or forwarding track 10, leading from a usual cashier's station (not shown) and an incoming or return track 11, leading to said cashier's station. These tracks are composed of rails of any suitable cross-sectional shape, as for example cylindrical rods, herein two in number for each track, and suitably supported in any usual or desired manner. Associated with these tracks, is a suitable driving element, herein an endless motor cable 12, which in practice will be suitably tensioned and driven, and which it will be convenient hereinafter to refer to as the main cable.

The tracks 10 and 11 are adapted to sustain and guide suitable carriers 13, having provision for engaging the tracks, and herein consisting of pairs of guides 14-14, on opposite sides of the carrier, separated by grooves 15 adapted to receive the rails of the track. The carriers are provided with suitable cable-gripping devices herein comprising a fixed arm 16 and a pivoted arm 17, the latter being pivoted at 18 to the body of the carrier, and preferably provided with a cam 19 engaging a spring 20 serving to maintain the arm in either a closed position as shown in Fig. 7 or an open position as shown in Fig. 5. When the pivoted arm is in its closed position, the spring serves to supply the necessary pressure to urge the arm against the cable 12, and consequently pinch or grip the cable against the fixed arm 16. When the pivoted arm is in its open position, the spring serves to maintain the arm in such position out of engagement with the cable, as clearly illustrated in Fig. 9, until it is closed by a cam. Herein the arm 17 is provided with a cable receiving notch or depression 21, as is usual with devices of this character; but the arm 16, instead of being notched or grooved, is provided with a substantially flat cable engaging face 22, for a purpose which will be hereinafter explained.

Preferably, though not necessarily, the rails of the track 10 are disposed in a horizontal plane, so that the carrier travels flat-wise thereon, while the rails of the track 11 are disposed in a vertical plane, so that the carrier travels edge-wise thereon. It will be understood that in practice, the tracks 10 and 11 may connect one or more drop sta-

tions with the cashier's station, but for the purpose of the present invention, it will suffice to show and describe merely one of these drop stations. It will be understood that 5 the tracks 10 and 11 will be located at some distance above the counters of the store, usually a distance of several feet.

I will now describe the drop station, by means of which the carriers are diverted 10 from the main outgoing track into the drop station and are returned therefrom to the main incoming track. Herein the drop station comprises a drop receiving track 23, extending from a point adjacent the main 15 outgoing track 10 to a point at or adjacent the counter (not shown). Preferably this track is provided with a horizontal portion 24, herein located above the track 10, and a vertical portion 25, leading downwardly to 20 the counter.

In connection with the drop station receiving track 23, I employ suitable means for selectively and automatically diverting from the main outgoing or forwarding track 25 10 such of the carriers as are intended for this particular drop station. For this purpose, I employ suitable means to engage the carriers of a certain configuration, size, or other characteristic. Herein the carrier diverting means just referred to comprises switch or diverting tracks 26—26 arranged in pairs, two on each side of the carrier and separated from each other by a slot 27, which receives supplemental guides 28—28, 30 provided on the carrier 13. These guides, as usual, will be placed at various heights upon the carriers, according to the station for which they are intended, and the diverting switch tracks 26—26 will be correspondingly 35 placed as to height from the outgoing or forwarding track 10. Such of the carriers as are not intended for this particular station will pass from left to right (Fig. 2) beneath the diverting or switch tracks 26, 40 and will pass along to the station for which they are intended. Such of the carriers as are intended for this particular station will be diverted from the track 10 by the engagement of the supplemental guides 28—28 45 with the switch or diverting tracks 26, so that the carrier, while still maintaining its hold upon the cable, will be lifted out of cooperation with the track 10, said track for this purpose being provided with suitable 50 offset portions 29—29 (see Fig. 2) to permit the main or principal guides 14—14 to clear such track. When the carrier is thus diverted from the main outgoing track, it still maintains its hold upon the cable for a 55 time, thus lifting the cable from its normal position, as shown in Fig. 6, and passes into cooperation with the horizontal portion 24 of the drop station receiving track 23, as clearly shown in Fig. 6, the guides 14—14 60 receiving the rails of said track as clearly

shown therein. After the carrier passes into coöperation with the track 23, as just described, it passes out of coöperation with the switch or diverting tracks 26, as will be evident from an inspection of Fig. 6. At this point, the carrier is disengaged from the cable by suitable means, herein a cam 30, which is engaged by the cable gripping arm 17 (see Fig. 7). The latter is 70 swung from the position shown in full lines therein to the position shown in dotted lines therein, thus releasing its hold upon the cable, which of course will snap back into its normal path. Since the arm 16 is provided with the flat cable engaging face 22, 80 as hereinbefore described, such release of the cable will occur without any interference by said arm. The cam 30 will in practice be supported in any usual or desired manner, as by means of a bracket 31, which herein 85 also serves as one of the supports of the tracks 26 and the horizontal portion 24 of the track 23. In connection with the tracks 26, I may employ if desired a suitable guard-rail 32, serving to steady the carrier and 90 maintain its proper engagement with said tracks.

When the carrier is released from its driving engagement with the cable as just described, it travels by its momentum down 95 along the drop receiving track 23, and there may be provided a suitable buffer 33 to receive its impact. The drop receiving track 23 has suitable provision for the removal of the carrier therefrom, herein consisting of 100 offset portions 34—34, from which the principal guides 14 of the carrier may be withdrawn in a well-known manner by lifting the carrier and rocking it laterally.

I will now describe the means by which the carrier is sent from the drop station and placed in coöperation with the main incoming or return track 11, and which forms one of the principal features of my present invention: Leading upwardly from the counter is a station sending track 35, having suitable provision for the introduction of the carrier, herein offset portions 36—36, similar to those of the receiving track hereinbefore described. This sending track extends to a point adjacent the main incoming or return track 11, and herein extends alongside the latter, preferably in a plane parallel thereto, as seen in Figs. 2 and 3. Associated with this station sending track is an auxiliary 110 endless motor cable 37, having a vertical portion 38 arranged alongside the vertical portion of the track 35, and a substantially horizontal portion 39 arranged alongside the corresponding substantially horizontal portion 40 of the track 35, so as to engage and drive the carriers in coöperation with said track. This auxiliary cable may be driven in any suitable manner, herein receiving its power from the main cable 12. For this 115 120 125 130 135

purpose the lower strand of the main cable 12 passes over two grooved pulleys or wheels 41 and 42, and to insure a proper driving engagement therewith, the cable may be deflected from its normal or straight course between said wheels into arc contact therewith by suitable means, herein an idle grooved pulley, or wheel, 43. This deflection of the main cable makes it necessary to provide the main incoming or return track 11 with a depressed portion 44, so as to maintain the coöperation of the carrier with the cable at this point.

The pulleys 41 and 42 drive similar pulleys 45 and 46 respectively. The latter pulleys receive and drive the auxiliary cable 37, which passes part way around each of said pulleys, part way around the idle pulley 47, and part way around a take-up pulley 48. The latter pulley furnishes the necessary tension upon the auxiliary cable in a manner similar to that in which driving cables are ordinarily tensioned, said pulley being herein journaled upon a support 49, mounted to slide vertically upon the rails of the tracks 23 and 35. Secured to this support is a suitable tensioning device, herein cord 50, wound upon a drum 51, which in practice will be provided with a suitable weight or spring (not shown), which will furnish the desired tension. It will now be apparent that when the carrier is introduced upon the rails of the station sending track 35 at the openings or offset portions 36, its cable gripping device must immediately grip the cable so as to drive the carrier. For this purpose, I preferably provide a gripper actuating cam 52 (see particularly Fig. 5), which is adapted to engage the cable gripping arm 17 and throw the same from the position shown in Fig. 5 into operative engagement with the cable. The power for forcing the carrier against the cam as just described is furnished by the hand of the operator. When the carrier is thus engaged by the auxiliary cable, it is driven upwardly along the vertical portion of the station sending track 35, and thence along a substantially horizontal portion 40, from which it is switched laterally onto the main incoming or return track 11 by suitable switch or diverting track 23, similar to the tracks 26-26 hereinbefore described, and adapted to receive the supplemental guides 28-28 of the carrier, as will be evident from an inspection of Fig. 2. The main incoming or return track 11 has suitable provision, herein offset portions 54-54, which permit the principal guides 14-14 of the carrier to pass into coöperation with said track as the supplemental guides 28-28 pass out of coöperation with the switch tracks 53-53. It will now be evident that when the carrier is to pass out of coöperation with the auxiliary cable into coöpera-

tion with the main cable, there must be provided suitable instrumentalities to disengage the carrier from its driving engagement with the auxiliary cable, and subsequently engage the carrier in driving engagement with the main cable. To this end, I preferably employ a gripper actuating cam 55, similar to those hereinbefore described, arranged adjacent the substantially horizontal portion 37 of the auxiliary cable, and adapted to engage the cable gripping arm 17 to disengage the latter from the auxiliary cable. The carrier must then travel by its momentum along the remaining portion of the track 40 into coöperation with the switch tracks 53, and along the latter into coöperation with the main incoming or return track 11, at which point the carrier is engaged with the main cable by suitable means, herein a grip actuating cam 56, adapted to engage the gripper arm 17, and throw the latter into engagement with the main cable.

The carrier will have attained a high rate of speed during its driving engagement with the auxiliary cable, and under ordinary circumstances will successfully travel under its momentum from the disengaging cam 55 to the engaging cam 56; but in order to add somewhat to the speed of the carrier between these two points, and to insure its having sufficient speed when it strikes the latter cam, the portion 40 of the station sending track 35 may have a downward incline from right to left (Fig. 1), and the main incoming track 11 may be also similarly inclined. The latter track will then take an upward course to its normal level.

The general operation of the specific embodiment of my invention hereinbefore described is as follows: The carrier containing the money and sales slip is introduced on to the station sending track 35. It is engaged with the auxiliary cable, and is driven along the station sending track into coöperation with the main incoming or return track 11 and the main cable 12. When in coöperation with the latter track and cable, the carrier is carried to the cashier's station (not shown) at some distant point, as is customary, after which the change is made and the carrier is placed in coöperation with the main outgoing or sending track 10 and the main cable 12. The carrier passes along the latter track, and is diverted therefrom at its proper station by the diverting tracks 26 into coöperation with the drop receiving track 23, from whence it may be removed in the manner hereinbefore described.

While I have herein shown and described one form of my invention for illustrative purposes, and have disclosed and discussed in detail the construction and arrangement incidental to one specific embodiment thereof, it is to be understood that the invention

is limited neither to the present embodiment nor to its specific application herein shown, but that extensive deviations from the illustrated form or embodiment of the invention 5 may be made without departing from the principles thereof.

Having thus described one embodiment of my invention, what I claim is:

1. A cable carrier apparatus having, in combination, main and auxiliary endless tracks, main and auxiliary motor cables, a carrier, and means to transfer the driving engagement of the carrier from one to the other of said cables.
- 15 2. A cable carrier apparatus having, in combination, main and auxiliary tracks, main and auxiliary motor cables one driven by the other, a carrier, and means to transfer the driving engagement of the carrier 20 from one to the other of said cables.
- 25 3. A cable carrier apparatus having, in combination, main and auxiliary tracks, main and auxiliary motor cables, means driven by said main cable for driving said auxiliary cable, a carrier, and means automatically to transfer the driving engagement of the carrier from one to the other of said cables.
- 35 4. A cable carrier apparatus having, in combination, main and auxiliary endless tracks, main and auxiliary motor cables, a carrier, means to transfer said carrier from said main track to said auxiliary track, and means automatically to transfer the driving engagement of the carrier from one to the other of said cables.
- 40 5. A cable carrier apparatus having, in combination, main and auxiliary tracks, a carrier having principal guides adapted to coöperate with said main and auxiliary tracks, and having also supplemental guides, main and auxiliary endless motor cables adapted to propel said carrier along said tracks, means to coöperate with said supplemental guides to guide said carrier out of coöperation with said auxiliary track into coöperation with said main track, and means automatically to transfer the driving engagement of the carrier from the auxiliary 50 cable to the main cable.
- 55 6. A cable carrier apparatus having, in combination, main track and auxiliary tracks, a carrier, main and auxiliary endless motor cables adapted to propel said carrier along said main and auxiliary tracks, a wheel driven by said main cable, a second wheel driven by the first and arranged to drive said auxiliary cable, means for causing said carrier operatively to engage said auxiliary cable, means for causing said carrier to disengage from said auxiliary cable, and means for causing said carrier to operatively engage said main cable.
- 65 7. A cable carrier apparatus having, in combination, main track and auxiliary
- tracks, a carrier, main and auxiliary endless motor cables adapted to propel said carrier along said main and auxiliary tracks, a pair of wheels driven by said main cable, a second pair of wheels driven by the first and arranged to drive said auxiliary cable, means for causing said carrier operatively to engage said auxiliary cable, means for causing said carrier to disengage from said auxiliary cable, and means for causing said carrier to operatively engage said main cable. 70
8. A cable carrier apparatus having, in combination, main track and auxiliary tracks, a carrier, main and auxiliary endless motor cables adapted to propel said carrier along said main and auxiliary tracks, a pair of wheels driven at different points by said main cable, means to deflect said main cable from its normal course into contact with said wheels, and means driven by said wheels for driving said auxiliary cable. 80
9. A cable carrier apparatus having, in combination, main track and auxiliary tracks, a carrier, main and auxiliary endless motor cables adapted to propel said carrier along said main and auxiliary tracks, a wheel engaging and driven by said main cable, means to compel arc contact of said main cable with said wheel, and means driven by said wheel for driving said auxiliary cable. 90
10. A cable carrier apparatus having, in combination, a main track having a depression therein, an auxiliary track, a carrier, a main endless motor cable adapted to propel said carrier along said main track, an auxiliary endless motor cable adapted to propel said carrier along said auxiliary track toward said main track, wheels engaging and driven by said main cable at opposite sides, respectively, of said depression, means to deflect said main cable from its normal course adjacent said depression and between said wheels thereby to compel arc contact of said main cable with said wheels, and means driven by said wheels for driving said auxiliary cable. 100
- 105 11. A cable carrier apparatus having, in combination, a main track, an auxiliary track extending from a point below said main track to a point adjacent the latter, a carrier, a main endless motor cable adapted to propel said carrier along said main track, and an auxiliary endless motor cable adapted to propel said carrier upwardly along said auxiliary track into coöperation with said main track and main cable. 115
- 120 12. A cable carrier apparatus having, in combination, a main track, an auxiliary track extending from a point below said main track to a point adjacent the latter, a carrier, a main endless motor cable adapted to propel said carrier along said main track, and an auxiliary endless motor cable. 125
- 130

driven by said main cable adapted to propel said carrier upwardly along said auxiliary track into coöperation with said main track and main cable.

5 13. A cable carrier apparatus having, in combination, a main track, an auxiliary track extending from a point below said main track to a point adjacent the latter, a carrier, a main endless motor cable adapted to 70 propel said carrier along said main track, an auxiliary endless motor cable adapted to propel said carrier along said auxiliary track toward said main track, and means driven by said main cable for driving said 75 auxiliary cable.

15 14. A cable carrier apparatus having, in combination, a main track, an auxiliary track extending from a point below said main track to a point adjacent the latter, a carrier, a main endless motor cable adapted to 80 propel said carrier along said main track, an auxiliary endless motor cable adapted to propel said carrier along said auxiliary track toward said main track, a wheel driven by said main cable for driving said auxiliary cable, and means for compelling arc contact of said main cable with said wheel.

20 15. A cable carrier apparatus having, in combination, a main track or way, a carrier adapted to travel on said track or way, a main 85 endless motor cable adapted to propel said carrier along said track or way, means including an auxiliary endless motor cable for placing said carrier in coöperation with said track or way, an independent drop receiving track or way, and means for diverting said carrier from said main track or way into coöperation with said drop receiving track or way.

25 16. A cable carrier apparatus having, in combination, a main track or way, a carrier adapted to travel on said track or way, a main 90 endless motor cable adapted to propel said carrier along said track or way, means including an auxiliary endless motor cable for placing said carrier in coöperation with said track or way, an independent drop receiving track or way, and means for diverting said carrier from said main track or way into coöperation with said drop receiving track or way, and means automatically to disengage said 95 carrier from said main cable.

30 17. A cable carrier apparatus having, in combination, an outgoing or forwarding track, an incoming or return track, a carrier 100 adapted to travel on said tracks, a main endless motor cable adapted to propel said carrier along said tracks, means including an auxiliary endless motor cable for placing said carrier in coöperation with said incoming or return track, and main cable, an independent drop or receiving track, and means for diverting said carrier from said outgoing or forwarding track into coöperation 105 with said drop receiving track or way.

18. A cable carrier apparatus having, in combination, an outgoing or forwarding track, an incoming or return track, a carrier adapted to travel on said tracks, a main endless motor cable adapted to propel said carrier along said tracks, means including an auxiliary endless motor cable for placing said carrier in coöperation with said incoming or return track and main cable, an independent drop receiving track, means for diverting said carrier from said outgoing or forwarding track into coöperation with said drop receiving track or way, and means for automatically disengaging said carrier from 110 said main cable.

19. A cable carrier apparatus having, in combination, a main track or way, a carrier adapted to travel on said track or way, a main endless motor cable adapted to propel said carrier along said track or way, means including an auxiliary endless motor cable driven by said main cable for placing said carrier in coöperation with said track or way, an independent drop or receiving track or way, and means for diverting said carrier from said main track or way into coöperation with said drop receiving track or way.

20. A cable carrier apparatus having, in combination, a main track or way, a carrier adapted to travel on said track or way, a main 115 endless motor cable adapted to propel said carrier along said track or way, means including an auxiliary endless motor cable driven by said main cable for placing said carrier in coöperation with said track or way, an independent drop or receiving track or way, and means for diverting said carrier from said main track or way into coöperation with said drop receiving track or way, and means automatically to disengage said 120 carrier from said main cable.

21. A cable carrier apparatus having, in combination, a main track or way, a carrier adapted to travel on said track or way, a main endless motor cable adapted to propel said carrier along said track or way, means including an auxiliary endless motor cable for placing said carrier in coöperation with said track or way, means driven by said main cable for driving said auxiliary cable, 125 an independent drop or receiving track or way, and means for diverting said carrier from said main track or way into coöperation with said drop receiving track or way.

22. In a cable carrier apparatus, the combination with a main track, and a main cable, of a carrier, the auxiliary sending track 35, and auxiliary cable 37 associated with said auxiliary track.

23. In a cable carrier apparatus, the combination with a main track, and a main cable, of a carrier, the auxiliary sending track 35 and switch track 53, and the auxiliary cable 37 associated with said auxiliary track.

24. In a cable carrier apparatus, the combination with a main track and main cable, of a carrier, the auxiliary sending track 35, auxiliary cable 37, associated with said auxiliary track, gripper-closing cam 52, gripper-opening cam 55, and gripper-closing cam 56.
25. In a cable carrier apparatus, the combination with a main track and main cable, of a carrier, the auxiliary sending track 35, auxiliary cable 37 driven by the main cable, and means for effecting a transfer of the driving connection of the carrier from the cable 37 to the main cable.
- 15 26. In a cable carrier apparatus, the combination with a track and a motor cable associated therewith, of a carrier having a pair of cable grippers projecting from one side thereof, adapted to engage and grip the 20 cable therebetween, said grippers having provision permitting withdrawal of the cable laterally in its normal plane, and substantially at right angles to said side, means to relatively actuate said grippers to release 25 the cable, and means to cause said carrier to move laterally to effect the withdrawal of the cable from between said grippers.
27. In a cable carrier apparatus, the combination with a track and a motor cable associated therewith, of a carrier having a fixed and a movable gripper projecting from one side thereof adapted to engage and grip the cable therebetween, said movable gripper being recessed to receive the cable and said 35 fixed gripper being substantially unrecessed.
28. A cable-carrier apparatus having, in combination, main and auxiliary tracks, main and auxiliary endless motor cables, a
- carrier having cable-gripping means, and engaging and disengaging means automatically to transfer the driving engagement of said cable-gripping means from one to the other of said cables. 40
29. A cable carrier apparatus having, in combination, main and auxiliary tracks, main and auxiliary endless motor cables, a carrier having cable-gripping means, means to disengage said cable-gripping means from its engagement with said auxiliary cable, and means to engage said cable-gripping means with said main cable. 45
30. A cable carrier apparatus having, in combination, main and auxiliary tracks, main and auxiliary endless motor cables, a carrier having cable-gripping means, means to engage said cable-gripping means with said auxiliary cable, means to disengage said cable-gripping means from said auxiliary cable, means to engage said cable-gripping means with said main cable, and means to 50 disengage said cable-gripping means from said main cable. 55
31. A cable carrier apparatus having, in combination, main and auxiliary tracks, main and auxiliary endless motor cables, a carrier, and means automatically to transfer the carrier from one to the other of said tracks and the driving engagement of the carrier from one to the other of said cables. 60

In testimony whereof, I have signed my name to this specification, in the presence of two subscribing witnesses.

Copies of this patent may be obtained for five cents each, by addressing the "Commissioner of Patents, Washington, D. C."

Corrections in Letters Patent No. 1,055,258.

It is hereby certified that in Letters Patent No. 1,055,258, granted March 4, 1913, upon the application of Louis W. Chism, of Springfield, Massachusetts, for an improvement in "Cable Carrier Apparatus," errors appear in the printed specification requiring correction as follows: Page 4, lines 10 and 30, strike out the word "endless" and same page, lines 11 and 31, after the word "auxiliary" insert the word *endless*; and that the proper corrections have been made in the files and records of this office and are hereby made in the said Letters Patent.

Signed and sealed this 8th day of April, A. D., 1913.

[SEAL.]

C. C. BILLINGS,
Acting Commissioner of Patents.

24. In a cable carrier apparatus, the combination with a main track and main cable, of a carrier, the auxiliary sending track 35, auxiliary cable 37, associated with said auxiliary track, gripper-closing cam 52, gripper-opening cam 55, and gripper-closing cam 56.
25. In a cable carrier apparatus, the combination with a main track and main cable, of a carrier, the auxiliary sending track 35, auxiliary cable 37 driven by the main cable, and means for effecting a transfer of the driving connection of the carrier from the cable 37 to the main cable.
- 15 26. In a cable carrier apparatus, the combination with a track and a motor cable associated therewith, of a carrier having a pair of cable grippers projecting from one side thereof, adapted to engage and grip the 20 cable therebetween, said grippers having provision permitting withdrawal of the cable laterally in its normal plane, and substantially at right angles to said side, means to relatively actuate said grippers to release 25 the cable, and means to cause said carrier to move laterally to effect the withdrawal of the cable from between said grippers.
27. In a cable carrier apparatus, the combination with a track and a motor cable associated therewith, of a carrier having a fixed and a movable gripper projecting from one side thereof adapted to engage and grip the cable therebetween, said movable gripper being recessed to receive the cable and said 35 fixed gripper being substantially unrecessed.
28. A cable-carrier apparatus having, in combination, main and auxiliary tracks, main and auxiliary endless motor cables, a
- carrier having cable-gripping means, and engaging and disengaging means automatically to transfer the driving engagement of said cable-gripping means from one to the other of said cables. 40
29. A cable carrier apparatus having, in combination, main and auxiliary tracks, main and auxiliary endless motor cables, a carrier having cable-gripping means, means to disengage said cable-gripping means from its engagement with said auxiliary cable, and means to engage said cable-gripping means with said main cable. 45
30. A cable carrier apparatus having, in combination, main and auxiliary tracks, main and auxiliary endless motor cables, a carrier having cable-gripping means, means to engage said cable-gripping means with said auxiliary cable, means to disengage said cable-gripping means from said auxiliary cable, means to engage said cable-gripping means with said main cable, and means to 50 disengage said cable-gripping means from said main cable. 55
31. A cable carrier apparatus having, in combination, main and auxiliary tracks, main and auxiliary endless motor cables, a carrier, and means automatically to transfer the carrier from one to the other of said tracks and the driving engagement of the carrier from one to the other of said cables. 60

In testimony whereof, I have signed my name to this specification, in the presence of two subscribing witnesses.

C. C. BILLINGS,
Acting Commissioner of Patents.

It is hereby certified that in Letters Patent No. 1,055,258, granted March 4, 1913, upon the application of Louis W. Chism, of Springfield, Massachusetts, for an improvement in "Cable Carrier Apparatus," errors appear in the printed specification requiring correction as follows: Page 4, lines 10 and 30, strike out the word "endless" and same page, lines 11 and 31, after the word "auxiliary" insert the word *endless*; and that the proper corrections have been made in the files and records of this office and are hereby made in the said Letters Patent.

Signed and sealed this 8th day of April, A. D., 1913.

[SEAL.]

C. C. BILLINGS,
Acting Commissioner of Patents.
